(57) **CLAIM**

The ornamental design for a mounting bracket, as shown and described.

DESCRIPTION

FIG. 1 is a top view of a mounting bracket;

FIG. 2 is a front view thereof; the back view being a mirror image;

FIG. 3 is a bottom view thereof;

FIG. 4 is a right side view thereof;

FIG. 5 is a left side view thereof;

FIG. 6 is an isometric view thereof; and

FIG. 7 is an isometric view thereof, shown with environment;

FIG. 8 is a top view of a second embodiment of the mounting bracket;

FIG. 9 is a front view thereof; the back view being a mirror image;

FIG. 10 is a bottom view thereof;

FIG. 11 is a right side view thereof;

FIG. 12 is a left side view thereof;

FIG. 13 is an isometric view thereof; and,

FIG. 14 is an isometric view thereof, shown with environment.

The broken lines in FIGS. 7 and 14 show features associated with the mounting bracket in a condition of use, and which forms no part of the claimed invention.

The broken line showing of environment in FIG. 7 and 14 is for the purpose of illustrating environmental structure and forms no part of the claimed design.

1 Claim, 6 Drawing Sheets
